UNITED STATES PATENT OFFICE.

ALVA J. CARTER, OF CHICAGO, ILLINOIS, ASSIGNOR TO CARTER RADIO COMPANY, OF CHICAGO, ILLINOIS, A CORPORATION OF ILLINOIS.

PLUG.

Application filed July 6, 1925. Serial No. 41,692.

My invention relates to plugs and more particularly to an electrical plug particularly useful in connection with radio receiving apparatus.

It is a purpose of my invention to provide a plug that is adapted for cooperation with a jack such as used in connection with radio receiving apparatus and telephone apparatus having a tip and a sleeve that are insulated from each other, said insulating means spacing said tip and sleeve from each other and being of smaller diameter than said tip and sleeve to prevent short circuiting of the plug across the insulation. This short circuit is caused frequently due to the fact that the metal of the springs forming the contacts of the jack is deposited on the insulating member due to the spring scraping over the same thus making a line or continuous mark of a metal coating or deposit on the insulating member between the tip and the sleeve causing a short circuit between the tip and the sleeve. By setting the insulating member inwardly, contact of the springs with the insulating member is prevented thus preventing the deposit of metal thereon.

It is another purpose of the invention to provide a plug of the above mentioned character that is provided with the contacts seated in suitable openings in the body portion of the plug with which the plugs or terminals are adapted to cooperate to connect the receiver or other sound reproducing device electrically with the tip and sleeve of the plug and to provide resilient means for forcing said plugs or terminals into engagement with said contacts. Said resilient means preferably comprises a U-shaped insulating member of flexible material between the legs of which is mounted a spring tending to force the same apart. Preferably, the openings in the body portion of the plug are in the form of passages or channels that converge inwardly and are provided with abutments or fulcrums opposite the contacts so that when the plugs or terminals on the receiver or other sound reproducing means are inserted and engage with the U-shaped member, the resilient means tilts said ter-

minals or plugs around the abutments or fulcrums to force the same into engagement with the contacts. The resilient means lies inwardly of the abutments and the contacts lie outwardly thereof.

It is another purpose of the invention to provide a plug having a sleeve portion projecting therefrom with means for securing a contact thereto and to the body portion of the plug that simultaneously secures the sleeve to the body portion of the plug.

Other objects and advantages of the invention will appear as the description of the accompanying drawing proceeds. However, I desire to have in distinctly understood that I do not intend to limit myself to the exact details shown or described, but that I intend to include as part of my invention all such obvious changes and modifications of parts as would occur to a person skilled with this art and as would fall within the scope of the claims.

In the drawings:

Fig. 1 is a plan view of my improved plug with the cover removed;

Fig. 2 is a section thereof taken on the line 2—2 of Fig. 1 showing the cover in position;

Fig. 3 is a perspective view of one of the contacts used in the plug; and

Fig. 4 is a similar view of the other contact.

Referring in detail to the drawings, my improved plug comprises a body portion 10 of insulating material which has a hollow boss 11 projecting therefrom. Extending outwardly from the boss 11 is the sleeve 12 of conducting material which is provided with a reduced portion 13 to provide a shoulder 14 adapted to engage with the outer end of the boss 11. Mounted within the outer end of the sleeve 12 is an insulating sleeve 15 having a reduced portion 16 entering the end of the sleeve 12 and an enlarged portion 17 of smaller diameter than the outer diameter of the sleeve 12. The sleeve 15 is provided for spacing the extension 18 of the tip 19 from the sleeve 12. The tip 19 is of the usual outer contour for tips of telephone plugs and is provided with

a cylindrical portion 20 of substantially the same external diameter of the sleeve 12. Said tip is further provided with a concave annular groove 21 for receiving the convex end 22 of the insulating member 15.

A contact 23 having the flat ear 24 thereon lying adjacent the inner face 25 of the body portion 10 is provided in said plug. Said contact 23 is secured in electrical contact with the sleeve 12 and the sleeve 12 and the contact 23 are secured to the body portion 10 by upsetting or riveting over the sleeve 12 as indicated at 25 thus clamping the contact 23 and the boss 11 between the shoulder 14 and the head 25 on the sleeve 12.

The body portion 10 is provided with a pair of channels 26 and 27 that converge from the open end thereof toward the inner portion of the plug and open up into the enlarged recess or opening 28 which lies on the opposite side of the central opening in the boss 11 from the passages 26 and 27. The contact 23 lies in the passage 26 and is provided with a right angular end portion or finger 28 projecting into the passage 26.

The extension 18 has an insulating sleeve 28 mounted thereon which is provided with a reduced end portion 29 fitting between the stem 18 and the sleeve 12 to space the same at the inner ends thereof. The inner end of the member 18 is threaded as indicated at 30 and the ear 31 on the contact member 32 is mounted thereon in engagement with the insulating sleeve 28, said sleeve spacing the contacts 23 and 32 from each other. The nut 33 screw-threadedly engages with the threaded end 30 of the member 18 to clamp the contact 23 in engagement therewith. The ears 24 and 31 of the contacts 23 and 32 lie in a recess 34 formed between the wall 35 and the projection 36 of the body portion 10, the side walls of said ears converging as indicated at 37 and 38 and 39 and 40 respectively. The nuts of the ears are rounded as indicated at 41 and 42, and 43 and 44 respectively to conform to the curved faces of the projection 36 and the wall 35. The ear 24 is provided with an opening 45 of a size to receive the sleeve 12 and the ear 31 is provided with an opening 46 of a size to receive the stem 18. The contact 32 is provided with a projection or finger 47 corresponding to the finger 28 on the contact 23 and lies in the opening or passage 27.

Mounted between the ears 25 and 31 and having a curved bight portion 48 is the U-shaped insulating member 49 which is provided with flaring leg portions 50. The curved portion 48 thereof lies substantially in engagement with the curved wall portion 35 and a coil compression spring 51 lies between the legs 50 of the member 49 be-

tween the projection 36 and the rear wall portion 52 of the plug. An inward projection 53 is provided on the wall portion 52 to hold the spring 51 in position. The movement of the member 49 sidewise is limited by engagement of the legs 50 with the converging walls 54 of the recess 28.

It will be noted that offsets or abutments are provided at 55 between the converging wall portions 54 and the converging wall portions 56 of the passages 26 and 27. Upon reference to Fig. 1 it will be seen that when the plug or terminals 57 having the reduced end portions or tips 58 are inserted in the openings 27 and 26, the extreme end portions thereof will first engage with the member 49 as shown at the left of Fig. 1, the enlarged rear portion of the plug 57 sliding over the finger 47 or 28, as the case may be, of the contact in the passage. This continues until the end of the enlarged portion of the plug or terminal 57 passes the finger on the contact 23 or 32 whereupon the same will fulcrum around the abutment 55 due to the action of the spring 51 causing the plug to snap in back of the finger on the contact as shown at the right of Fig. 1, thus securely locking the terminal in position and making a good contact between the terminal on the conductor 59 and the contact 23. When it is desired to disengage the terminal or plug 57 from the contact with which it is in engagement, all that is necessary is to pull the same laterally away from the center of the plug compressing the spring 51 and tilting the member 51 so that the enlarged end thereof will pass the finger on the contact.

The plug is closed by means of the insulating cover member 60 which engages with the body portion 10 and which is provided with a central recess 61 to provide room for the members 30 and 33. Any suitable securing devices are used for securing the cover 60 on the body portion 10, the openings 62 being provided in the body portion 10 for the reception of said securing means.

Having thus described my invention what I desire to claim and secure by United States Letters Patent is:

1. In a plug of the character described, an insulating body portion, a pair of contacts mounted therein, terminal receiving openings in said body portion in which said contacts lie and resilient means for moving the terminals in said openings into engagement with said contacts comprising a U-shaped flexible member having a spring mounted between the arms thereof.

2. In a plug of the character described, an insulating body portion having a pair of converging passages therein, a contact lying adjacent one of the walls of each of said passages, and resilient means engaging ter-

minals inserted in said passages to move the same into engagement with said contacts.

3. In a plug of the character described, an insulating body portion having a pair of converging passages therein, a contact lying adjacent one of the walls of each of said passages, an abutment on the walls of

each of said passages opposite said contacts, and resilient means engaging terminals inserted in said passages inwardly of said abutments to force said terminals into engagement with said contacts. ¹⁰

In witness whereof, I hereunto subscribe my name this 2d day of July A. D., 1925.

ALVA J. CARTER.
